UNITED STATES PATENT OFFICE.

OTTO FABER, OF LA PORTE, TEXAS.

CEMENT INTERLOCKING PLATE.

1,420,246.

Specification of Letters Patent. Patented June 20, 1922.

Application filed March 31, 1919. Serial No. 286,303.

To all whom it may concern:

Be it known that OTTO FABER, citizen of Germany, residing at La Porte, in the county of Harris and State of Texas, has invented 5 new and useful Improvements in Cement Interlocking Plates, of which the following is a specification.

The purpose of the invention is to provide a cement plate or slab formed with 10 means for interlocking it with others of the same kind so that a hollow wall may be built with the inner section spaced from the outer section. The plate is of such a character that those comprising the inner section of 15 the wall have their points broken, or staggered with respect to those comprising the outer section. The plate in use is designed to stand upright—that is, it is placed in the wall of which it is a part so that it stands 20 vertical in the direction of its length and it is intended that the plates shall be made of a length suitable to the height of the wall which they are to form.

The invention is illustrated and described 25 in a specific embodiment to which it is not to be restricted. The right is reserved to make such changes or alterations as the actual reduction to practice may suggest in so far as such changes or alterations are 30 compatible in spirit with the annexed claim.

In the accompanying drawings:

Figure 1 is a horizontal sectional view 35 through a corner wall constructed with the improved plates.

Figure 2 is a horizontal sectional view 40 through one of the plates.

Referring to the drawings, the invention is shown as comprising a concrete slab or plate 8 which has the flange portions 9, these 45 flange portions 9 on their outer faces being provided with the semicircular depressions or grooves 10 but the plates 8 intermediate between the flange portions are provided with a third longitudinal flange portion 11 whose opposite faces are at right angles to 50 the outer face of the plate 8, and formed each with a depression 10, and therefore parallel with the outer faces of the flange portions 9. These plates 8 and their flange 55 portions 9 and 11, are provided with the reinforcements 3 and 4. In assembling the plates 8 to form a wall, as shown in Fig.

1, a plurality of upstanding plates is employed to form the outer wall and the inner wall is similarly formed, the two walls having their flange portions oppositely disposed, but the intermediate flanges of the outside plates stand between the edge flanges 9 of the inside plates and similarly the intermediate flanges of the inside plates stand between the edge flanges of the outside plates, thus positioning each depression 10 on each outside plate opposite a depression 10 on each inside plate. The double row of plates is set upon a suitable foundation and when 60 placed as shown in Figure 1, the spaces between the inner and outer walls are filled with a strong cement mortar to a height of about one and one-half inches, the mortar resting upon the foundation and adhering 65 to the inner faces of the body portions of the plates and the inner faces of the end flanges thereof, thus securing the plates to the foundation. The securing of the plates together is then completed by pouring a thin 70 cement mortar in the joints or keys comprising the facing semi-circular depressions 9 and 10 in adjacent flange portions.

With the construction shown in Fig. 1 the inner and outer walls are positively interlocked and this arrangement is provided to 75 suit the needs of heavy construction.

The invention having been described, what is claimed as new and useful is:

A wall structure consisting of inner and 80 outer interlocking wall elements of which each comprises a plurality of plates consisting of slab like bodies formed at each longitudinal edge with flange portions extending the full lengths of the bodies, the latter 85 being further formed with intermediate flange portions extending the full length of the body and disposed between the end flanges of adjacent plates of the opposite wall, the extremities of the intermediate 90 flange portions being exposed at the outer face of the opposite wall, the adjoining faces of adjacent flanges being formed with intermediate 95 disposed seats for the reception of keys.

In testimony whereof he affixes his signature.

OTTO FABER.
